(57) **CLAIM**

The ornamental design for a body sculpting garment as shown and described.

DESCRIPTION

FIG. 1 is a front view of a body sculpting garment according to a first embodiment of the design;

FIG. 2 is a rear view thereof;

FIG. 3 is a right side view thereof;

FIG. 4 is a front view of a body sculpting garment according to a second embodiment of the design;

FIG. 5 is a rear view thereof;

FIG. 6 is a right side view thereof.

FIG. 7 is a front view of a body sculpting garment according to a third embodiment of the design;

FIG. 8 is a rear view thereof; and,

FIG. 9 is a right side view thereof.

The broken lines illustrating a model and the straps of the garment in FIGS. 1-9 form no part of the claimed design. In FIGS. 4-9, the broken lines along the trimmed edges and seams of the garment depict stitching that forms part of the claimed design.
